Attorney: Mr. Wallace White

UNITED STATES PATENT OFFICE.

WALTER GEORGE BASS, OF LONDON, ENGLAND.

THEATER AND LIKE SEAT, CHAIR, AND THE LIKE.

Application filed March 14, 1923. Serial No. 624,940.

To all whom it may concern:

Be it known that I, WALTER GEORGE BASS, subject of King George of Great Britain, residing at 4 Amberley Road, Sydenham, London, S. E., England, have invented new and useful Improvements in or Connected with Theater and like Seats, Chairs, and the like, of which the following is a specification.

10 This invention relates to theater and like seats, chairs and the like.

The invention has for one of its objects to provide tip-up and like seats, for picture and other theaters and the like, of such improved construction that the upholstery and other parts of same can be easily and quickly renewed or otherwise attended to by unskilled persons and at a minimum of cost.

Another object of the invention is to provide a construction of seat, chair or the like, which enables the seat proper or bottom or any other part to be removed and replaced without the necessity for disturbing the standards or main frame of the seat, chair or the like, from the floor or in any other manner.

According to one feature of the invention the upholstered element or elements of the seat, chair or the like is or are easily detachable from the standards or main frame of the latter, and the parts are so constructed that they are formed separate from one another, are detachably secured to each other, and can be individually renewed.

35 Another feature of the invention consists in that in a tip-up seat, the seat proper or bottom is made in two or more sections which embrace between them the pivot pins of said seat or bottom, carried by the standards or main frame, and are adapted to be detached from one another when it is desired to remove the seat or bottom from said pins and from the standards or main frame of the seat.

45 The invention will now be described with reference to the accompanying drawings, in which:—

Figure 1 is a perspective view with parts broken away and in section and illustrating a suitable manner of carrying out the invention in connection with a seat.

Figure 2 is an underneath plan of the seat, also with parts broken away, and

55 Figure 3 is a detail sectional elevation of the seat;

Figure 4 is a detail perspective view showing a modification;

Figure 5 is a front elevation of an upholstered unit of a suitable form of back for a seat.

Figure 6 is a rear elevation of the back with parts broken away, and

Figure 7 is a perspective view of the back complete;

Figure 8 is a perspective view, with parts broken away, illustrating a suitable manner of carrying out the invention in connection with an arm-rest,

Figures 9 and 10 are perspective views of an inner base plate and an outer base plate, respectively, for the arm-rest, and

Figure 11 is a perspective view of the arm-rest complete.

Like parts in the seat, back and arm-rest elements are designated by similar reference letters.

In carrying out the invention each upholstered element of the seat, chair or the like, such as the seat proper or bottom *a*, the back *b* and the arm-rests *c* may comprise a wooden, metal or other foundation block or frame *d*. The packing *f* and/or springs *g* of the element is or are enclosed within a canvas or other bag or case, and tapes, cords or the like, clips or other fasteners are secured to the bag or case and are adapted to be employed to detachably fasten the bag or case in position. The packing *f* may be enclosed within one compartment *h* of the bag or case, and the springs *g* and frame *d* be contained within another compartment *i*.

Figures 1 and 3, of said bag or case, or the packing and bag may be secured to the frame, and the compartment *i* and the springs may be dispensed with. In the construction shown the bag *h*, *i*, is provided with tapes or cords *j* which are passed through holes *k* formed in an inner corrugated metal or other base plate *l* and are tied under the latter, and other tapes or cords *m* are looped or tied to screw bolts *e* protruding from the under side of said base plate. The packing and bag may be used without the foundation block or frame *d*. The screw bolts may be carried by the foundation block or frame *d* instead of the plate *l*. The tapestry or other outer covering material *n* of the upholstered element is arranged over the bag or case *h*, *i*, and the block or frame *d*, if the latter is used,

and is detachably secured in position in any suitable manner, such as in the manner described in connection with the bag or case, and if tapes, cords or the like are employed these would enable the material to be adjusted and tightened in position as desired. The covering material *n* is illustrated as being provided with eyelets *o* which slip over the bolts *e*, and with a draw tape or cord *p* passed through eyelets or a hem around its edge. It will be appreciated that with this construction the tapestry or covering material, or the latter and the bag or case, packing and springs, can be easily removed from the plate *l* for renewing, cleaning, or other purposes.

In the case of the arm-rests, Figures 8 to 11, and the back of the seat, chair or the like, Figures 5 to 7, the plate *l* carrying the bag or case and the covering material is preferably detachably secured to a wooden, metal or other outer base-plate *q* by passing the screw-bolts *e* through holes *r* formed in said base-plate, and the latter is in turn 20 removably fastened to the standards or main frame of the seat such as by medium of the said bolts and by nuts screwed thereon, which nuts would, therefore, serve also to fasten the base plates to the arm-rests and 30 back.

In the case of the seat proper or bottom, Figures 1 to 4 a wooden, metal or other outer base-plate *q'*, is preferably provided as with the arm-rests and back, and in the case of 35 a tip-up seat the pivot pins *s* of same are arranged to engage said seat proper or bottom at a point disposed between the foundation block or frame *d* and said base plate *q'*, as in Figure 4, or between the latter and the inner base plate *l*, as in Figures 1 to 3, 40 the arrangement being such that when these two members are detached from one another the seat proper or bottom *a* is removable from the standards or main frame *t*, and this 45 without detaching the latter from the floor or otherwise interfering with same. When the foundation block or frame *d* and the base plate *q'* are made of wood, Figure 4, two opposed recessed metal plates *u* may be secured to each side of the seat proper or bottom, the two plates together forming a bearing *v* for the adjacent pivot pin, but when 50 said block or frame and/or the base plates is or are made of pressed steel or other metal, the plates *u* may be dispensed with, and the bearings may be formed integrally with the block or frame and/or with the base plates, such as by forming opposed depressions *w*, 55 Figures 1 to 3, in the latter. It will be appreciated from the above that the bearings are each formed in two halves adapted to be secured around and to be separated from the pivot pins.

An arm-chair may be constructed in the 60 manner above described, but in this case

the arm-rests could be formed by extending the sides of the back forwardly at the sides of the chair.

It will be appreciated that the employment of the bolts and nuts has a distinct advantage over the usual practice of securing the upholstered parts of a tip-up seat to the standards or main frame by means of screws, in that said bolts and nuts can always be tightened up if the upholstered parts work loose, whereas in the case of the usual screws these latter can be tightened a few times only, after which their threads will no longer bite in the wooden blocks or frames of said parts.

By constructing a seat, chair or the like in the manner above described, the same is rendered highly hygienic and enable of being easily and thoroughly cleaned of dust and other dirt. The cost of manufacture and upkeep of the seat, chair or the like will be small, and the various parts thereof can be made easily and cheaply by mass production. The inside parts of the seat, chair or the like will outlive many new outer 85 coverings, which latter and said inside parts may be standardized and be replaced by unskilled labour. Owing to the provision of the metal base plates, the seat chair or the like is less liable to catching fire than the ordinary type of seat or the like.

Having now particularly described and ascertained the nature of my said invention and in what manner the same is to be performed, I declare that what I claim is:—

1. A chair seat, arm, or the like, including a unit comprising an upholstered element and a base plate having means to which said element is detachably secured, and a lower base plate removably secured to said unit base plate through said means, said unit base plate and lower base plate being each offset to form a recess extending inwardly from the edge thereof, said recesses together forming a pivot receiving opening.

2. A chair seat, arm, or the like, including a unit comprising a base plate having studs, an upholstered element having means to detachably cooperate with said studs to secure said element and base plate together as a unit, and a covering for said element removably engaging said studs to arrange said covering in position on the element.

3. A chair seat, arm, or the like, including a unit comprising a base plate having studs, an upholstered element having means to detachably cooperate with said studs to secure said element and base plate together as a unit, and an outer base plate engaging said studs to secure said base plates together.

4. A chair seat, arm, or the like, including a unit comprising an upholstered element having tapes and a base plate having studs about which said tapes are secured to hold the element and base plate together as a

unit, and an outer base plate adapted to be fitted over said studs to removably secure said base plates together.

5. A chair seat, arm, or the like, including a unit comprising a base plate having studs, an upholstered element having tapes to be tied about said studs, a covering for the element having eyelets to engage over said

studs, and an outer base plate arranged to engage over said studs to secure the base plates together and to conceal and hold the element and covering connections on said studs. 10

In testimony whereof I have signed my name to this specification.

WALTER GEORGE BASS.
